UNITED STATES PATENT OFFICE

ALONZO E. RHOADES, OF HOPEDALE, MASSACHUSETTS, ASSIGNEE TO DRAPER CORPORATION, OF HOPEDALE, MASSACHUSETTS, A CORPORATION OF MAINE.

BATTERY-FEED FOR LOOMS.

1,317,823.

Specification of Letters Patent. Patented Oct. 7, 1919.

Application filed March 4, 1919. Serial No. 889,541.

To all whom it may concern:

Be it known that I, ALONZO E. RHOADES, a citizen of the United States, residing at Hopedale, county of Worcester, State of Massachusetts, have invented an Improvement in Battery-Feeds for Looms, of which the following description, in connection with the accompanying drawing, is a specification, like characters on the drawing representing like parts.

This invention relates to automatic filling replenishing looms in which a supply of filling carriers such as bobbins is maintained in a battery, hopper or feeder, and in which these filling carriers, when the supply of running filling is to be replenished, are successively transferred from the feeder to the lay, through the operation of automatic mechanism.

The invention has for its object to secure substantially the result secured by the invention made the subject of the patent to E. S. Stimpson No. 1,202,116 granted October 24, 1916, and in some respects the present invention is subsidiary thereto.

The battery or feeder and the general character of mechanism associated therewith for securing its rotation and for securing the discharge of the filling carriers therefrom is of a well known type. In this type the battery or feeder is rotatable through the agencies of a ratchet wheel rotatable therewith and a feed pawl operated from some moving part of the mechanism such as the transfferer device which transfers the filling carriers to the lay.

The object of the invention is to insure at all times the proper and effective cooperation of the feed pawl and the ratchet wheel so that the tooth of the feed pawl will in its actuating movement be positively directed into proper engagement with the proper tooth of the ratchet wheel and be seated firmly against the base thereof.

The object of the invention is to secure this proper and effective cooperation of the feed pawl by means of an extension on the feed pawl having a face in sliding engagement with the hub of the feeder.

The invention thus prevents any difficulty arising by reason of the tooth of the feed pawl coming into engagement with the wrong tooth of the ratchet wheel or into

engagement with the tip or point of the tooth of the ratchet wheel which in the former case would cause an improper operation of the mechanism, and in the latter case might result in the breakage of either the tooth of the ratchet wheel or the tooth of the feed pawl or so wear the parts as ultimately to lead to breakage.

These and other objects of the invention will appear more fully from the accompanying description and drawings and will be particularly pointed out in the appended claims.

The drawings illustrate so much of an automatic filling replenishing loom of the Northrop type as is necessary to a disclosure of the invention.

In the drawings—

Figure 1 is an end elevation partially in transverse section of a sufficient portion of the loom necessary to the disclosure of the invention with its preferred form embodied therein;

Fig. 2 is a top plan view of the main features of construction shown in Fig. 1;

Fig. 3 is a view similar to Fig. 1 with the parts shown in the position which they assume when the transfferer is at or near the limit of its downward or transferring movement;

Fig. 4 is a view similar to Fig. 1 with the parts shown in the position which they assume when the transfferer has reached a point in its ascending movement where the tooth of the feed pawl comes into engagement with the tooth of the ratchet wheel.

The general construction of this type of loom being well known and familiar needs no extended description. It includes the rotary battery, hopper or feeder 1 comprising two parallel disks of which only one is shown provided with seats 2 for the butts of the filling carriers, herein shown as bobbins, and having its hub 3 rotatably mounted on the fixed stud 4 rigidly secured to the loom frame. This hopper or feeder is also provided with a ratchet wheel 5 rotatable therewith, and the teeth of the ratchet wheel 5 preferably correspond in number with the seats 2 so that as the ratchet wheel is moved one tooth a filling carrier is brought into position for transfer. The usual transfferer arm 6 is pivotally mounted at 7 upon a

stand 8 secured to the loom frame. Upon the call for filling replenishment this transfer arm which extends in between the disks of the feeder moves downwardly engaging the filling carrier and transfers it from the feeder to the shuttle then located therebeneath on the lay.

The rotation of the feeder to present a fresh filling carrier in position for transfer 10 is secured by a feed pawl shown as a suitably shaped plate 9 carried by a pivot shaft 10 on the transfer arm 6. The tooth of this feed pawl is a projection 11 extending laterally from the plate 9 and properly shaped to engage with the ratchet teeth.

The plate 9 constituting the feed pawl is provided with an upwardly extending extension 12 presenting a face 13 opposite the hub 3 of the feeder and adapted to have a 20 sliding contact therewith. The extension 12 is preferably formed with a laterally extending lug or projection 14 so as to increase the width of the face 13 and consequently diminish the wear between this face and the hub 3. The contour of the face 13 is so 25 shaped as in coöperation with the hub 3 to give the required movement to the feed pawl.

It will be observed that the feed pawl at 30 its pivotal point 10 is carried by the transfer arm and consequently moves up and down with the transfer arm. When the feed pawl actuates the ratchet wheel 5 to rotate the feeder the feed pawl rests upon the head 15 of the transfer arm, the tooth 11 of the feed pawl is seated against a tooth of the ratchet wheel, and the feed pawl is moved bodily with the transfer arm in an upward direction about the pivot 7 of the 40 transfer arm to give the required actuating movement. When the transfer arm descends it carries with it the pivotal point 10 of the feed pawl and thus carries the tooth of the feed pawl downwardly to a position from which upon its actuating movement it may again engage a tooth of the 45 ratchet wheel.

The object of this invention is by means of the extension 12 and its face 13 in sliding engagement with the hub 3 of the feeder so to direct the path of the tooth of the feed pawl that a proper coöperative action of the tooth of the feed pawl with the teeth of the ratchet wheel may at all times be effected.

55 The parts are so constructed and arranged, as for example as shown in the drawings, that when the transfer arm 6 is in its lowermost position, as shown in Fig. 3, the extension 12 will have the upper portion of its face 13 resting against the hub 3. As the transfer arm ascends it carries upwardly the pivotal point 10 and the face 13 of the extension 12 slides upwardly on the hub 3 rocking the feed pawl about its 60 pivot. The parts are so proportioned that

as this movement takes place the tooth 11 of the feed pawl is guided into seating engagement with the base of the proper tooth of the ratchet wheel just about as the head 15 of the transfer arm comes into engagement with the bottom edge of the feed pawl 9 as shown in Fig. 4. Thus means are provided which effectively prevent the tooth of the feed pawl from striking against or catching any but the proper tooth of the ratchet wheel, which insures that the tooth of the feed pawl shall be seated firmly against the base of the proper tooth, and which insures a positive and accurate actuating movement. During the actuating 80 movement of the ratchet wheel the extension 12 need no longer be guided by the hub 3 and swings away therefrom until the transfer arm reaches its upper limit of movement and the required actuation of the 85 ratchet wheel has taken place as shown in Fig. 1.

Retrograde movement of the feeder is prevented by the usual detent pawl 16 pivoted at 17 to the stand 8 and movable 90 by gravity due to the weighted foot 18 to bring its tooth 19 into engagement with the teeth of the ratchet wheel. A lateral lug 20 carried by an extension 21 engages the inner periphery of the flange 22 of the ratchet 95 wheel to prevent accidental disengagement of the detent pawl and ratchet.

Means are also provided as usual by which the feed pawl may be thrown out of engagement with the ratchet wheel to enable the feeder to be rotated and set by hand and for this purpose the handle 23 is provided projecting laterally from the feed pawl in position to be grasped by the operator.

It will thus be seen that the construction provided is of a simple and efficient nature and one in which the movement of the feed pawl is so controlled by the coöperation of the extension 14 sliding on the hub 3 as to 100 eliminate any difficulty in the proper engagement of the feed pawl and ratchet tooth and as to secure the proper coöperation of the parts and prevent improper operation of the feeder and breakage of the 110 teeth.

Having fully described my invention, what I claim as new and desire to secure by Letters Patent is:

1. In a loom a rotatable filling feeder to 120 hold a series of filling carriers, a ratchet wheel rotatable therewith, a feed pawl, and an extension on said feed pawl having a face in sliding engagement with the hub of the feeder and acting to guide the feed pawl in 125 its actuating movement until its tooth is seated and to seat said tooth in engagement with the base of the tooth of the ratchet wheel to be actuated.

2. In a loom a rotatable filling feeder to 130

hold a series of filling carriers, a ratchet wheel rotatable therewith, a pivotally mounted transerrer arm, a feed pawl pivotally mounted on the transerrer arm, and 5 an extension on said feed pawl having a face in sliding engagement with the hub of the feeder whereby the movement of the feed pawl is jointly controlled by the move-

ment of the transerrer arm and by said extension to insure the proper coöperative action of the tooth of the feed pawl and the teeth of the ratchet wheel. 10

In testimony whereof, I have signed my name to this specification.

ALONZO E. RHOADES.
